FOREIGN PATENT DOCUMENTS

FR 723464 4/1932

* cited by examiner

Primary Examiner — Cynthia Underwood(74) *Attorney, Agent, or Firm* — Thomas P. O'Connell; O'Connell Law Firm(57) **CLAIM**

I claim the ornamental design for an arcuate guide for intravenous tubes, as shown and described.

DESCRIPTION

FIG. 1 is a perspective view of an arcuate guide for intravenous tubes showing my design;

FIG. 2 is a top plan view thereof;

FIG. 3 is a bottom plan view thereof;

FIG. 4 is a view in rear elevation thereof;

FIG. 5 is a view in front elevation thereof;

FIG. 6 is a right side elevational view thereof; and,

FIG. 7 is a left side elevational view thereof.
